TILTABLE PROJECTOR BASE STRUCTURE WITH INTEGRAL SOCKET MOUNT

Ernest W. Goldberg, Wilmette, Ill.

Application July 13, 1953, Serial No. 367,609

12 Claims. (Cl. 88—24)

This invention pertains to picture projectors and has as its principal object an improved base construction for such devices characterized by the provision of a one-piece molded base shell having an integrally-formed lamp socket structure which is economical to manufacture and assemble and which affords greatly improved ventilating advantages for the projection lamp as well as the associated optical system.

Another object is the provision of an integral base and socket structure in which the socket portion is provided with formations which locate the lamp receptacle accurately for focusing purposes while affording a range of movement thereto as well as certain air passages for circulation of cooling air in direct contact with the socket receptacle and base portions of a lamp carried therein.

Another object is the provision of a base construction of the class described which includes a simplified tilting structure providing for manipulation of a tilt control knob through a long or slow arc and in a substantially horizontal plane on a deck or ledge portion of the one-piece base shell.

Another object is the provision in a projector of a base construction including a base shell having an integrally formed lamp socket structure and mounted upon pivot lugs on a pedestal casting to rock relative to the latter, with a cross-strap held between the pivot lugs and base shell, and a tilting lever pivoted on the cross-strap and angled through a long cam slot on the pedestal and thence up through a long slot in a horizontal ledge in the base shell for ease of access and manipulation in tilting the projector.

A further object is the provision, in a combination base shell and pedestal combination such as last above characterized, of a simple mounting for a blower motor on the cross-strap carried between the pivot lugs and the base shell.

Additional objects and aspects of novelty and utility pertain to details of the construction and operation of the embodiment described hereinafter in view of the annexed drawings, in which:

Fig. 1 is a side elevation of the new projector;

Fig. 2 is another elevational view of the projector as seen in Fig. 1 with the lamp housing and lamp optical system removed;

Fig. 3 is a top plan view of the projector as seen in Fig. 2;

Fig. 4 is a perspective view of the base shell with integral socket structure;

Fig. 5 is a perspective view of the pedestal casting and associated tilting and motor assembly from which the shell of Fig. 4 has been removed;

Fig. 6 is a bottom plan view of the pedestal casting and base shell in assembled condition;

Fig. 7 is a fragmentary bottom plan view, to enlarged scale, of the integral lamp socket structure;

Fig. 8 is a top plan view of the socket structure shown in Fig. 7;

2

Fig. 9 is a vertical sectional detail through the socket structure as viewed along lines 9—9 of Fig. 8;

Fig. 10 is another vertical sectional detail through the socket structure taken along lines 10—10 of Fig. 9.

Referring to Fig. 1, the projector consists of a pedestal casting 10, upon which is rockably mounted a molded base shell 15 carrying a lens-barrel and slide-bed casting 16 and a removable lamp house 17. By loosening a knurled set screw 18, the lamp house or hood 17 can be removed to expose the lamp system for the purpose of renewing the lamp 19 (Fig. 2) or cleaning the reflector, condensing lenses, etc.

Referring to Fig. 4, the shell member 15 is preferably molded from a suitable plastic material to include an open well portion 20 surrounded on three sides by a skirt or sidewall portion 15A, and having a lowered deck 21 at the front thereof in which is formed an arcuate slot 22.

Molded integrally with the base shell 15 is a socket structure including a swept-back cross web having rearwardly-raked arms 23, 23A, and having a central socket cavity 24 shown more particularly in Figs. 7 to 10.

As seen in the bottom view of Fig. 7, the socket well is provided with a pair of diametrically opposite centering or locating bosses 25 (see also Figs. 8 and 9) located on the fore-and-aft or longitudinal axis of the shell and a line parallel to the optical axis through the lamp 19 and projecting lens means 16A, for the purpose of precisely locating the lamp 19 at a predetermined position of focus relative to the optical system.

In order to expose essential details of novelty to view in the several figures of drawing, the source optical system, ordinarily consisting of a concave reflector, a pair of condensing lenses, and a heat absorbing plate, has been omitted. However, it is well understood in the art that the lamp 19 must be critically focused relative to any focusing type reflector and condensing system if the highest optical efficiency is to be procured.

Referring still to Figs. 7 and 8, the socket structure further includes a metal ring or base receptacle 26 to receive the lamp base, and a pair of divergent wings or tabs 27 which are respectively engaged by adjusting screws 28.

As in the enlarged sectional view of Fig. 10, springs 29 are interposed between the mounting wings 27 and the socket body to provide a resilient seating for the lamp and also an adjusting instrumentality.

By turning the screws 28 in or out, the socket shell or receptacle 26 can be rocked transversely of the optical axis to center the lamp filament relative to a reflector (not shown).

The electrical contacts for the socket are completed by a spring contact arm 30 fixed on the web structure by a screw 31, and having an offset contacting end portion 30A underlying the center of the receptacle shell 26.

Referring to Fig. 3, there is provided in the base well, beneath the swept-back socket web 23, a fan 34, the hub portion of which is located beneath the socket well 24, it being important to observe that the foregoing construction, including the spacing of the socket shell 26 by bosses 25, the raking of the webs 23, 23A, and location of the fan hub beneath the socket shell, affords highest efficiency for cooling the lamp 19 within the limitations of space provided by the entire housing construction.

Thus it will be observed that a maximum unobstructed space is provided in the base well in the region between the lamp 19 and lens barrel 16, so that air can circulate most freely in the region between the lamp and slide bed 16B where it is needed to reduce the heating effect on the film.

The clearance between the socket shell 26 and well 24 affords a substantial air passage around the lamp

base. Moreover, there is also good circulation behind the lamp, with the web structure 23, 23A affording an optimum strength and minimum obstructiveness.

The base structure as shown in the related views of Figs. 4 and 5 provides a simple but efficient means for mounting the projector base shell 15 and blower or fan means 34.

Figs. 4 and 5 are in the relationship of an exploded perspective, in which the base shell 15 has been lifted off the pedestal casting 10.

The fan means 34 includes a small motor 35 carried on a simple cross-bar 36, which fits up against a pair of bosses 15B on the base shell, so as to be clamped between the latter and a pair of angle lugs 37 pivoted as at 38 in recessed offsets 39 on the casting. Screws 40 are passed up through the angle lugs, the cross-bar or bearer strap 36 for the motor, and threaded into the bosses 15B on the base shell, thus fixing the motor and fan in position beneath the lamp, and also attacking the shell rockably to the pedestal casting, with the motor and fan located at the pivot point for minimized change of relative positions between the fan and lamp socket structure.

A further feature of novelty is the means for rocking the projector base shell relative to the pedestal casting, and this includes a tilting lever 45 (Fig. 5) pivotally attached as at 46 to the motor bearer strap 36.

The free end of this tilting or rocking lever 45 passes through an inclined slot 47 (Fig. 5) in a plate 48 secured by screws 49 (Fig. 6) to the forward end of the pedestal casting, from whence the lever is offset upwardly as at 45A to pass through the arcuate slot 22 in the base shell, where the end of the lever engages in a handle element 50.

By swinging the lever across the slot 22, using handle 50, the lever arm 45, pivoting at 46, rides the sloping slot 47 and causes the base shell 15 and pedestal casting 10 to pivot, relatively, so as to lower or elevate the lens means 16A relative to a screen or the like.

Actually, the heavy pedestal casting remains at rest, and the trunnion means, including the two pivot lugs or angles 37 and the cross-strap 36 rock; and since the projector base member or shell 15 is engaged with, and in effect carried by, the trunnion means by engagement of the bolts 40 in shell bosses 15B, the latter moves responsive to manipulation of the tilt lever means.

It should be observed, by inspection of Figs. 3 to 6, that the shaft 34X of the motor fan or blower means substantially underlies the socket structure and lamp 19, and that the pivotal attachment 46 (Fig. 6) of the tilt lever lies along a line parallel to the rocking axis of the pivot lugs or trunnion means, so that between the opposite limits of travel of the tilt lever the axis of the blower fan 34 is displaced relatively little relative to the lamp 19 to insure good cooling circulation from beneath the lamp in all positions of tilt.

In this latter connection the annular space between the socket receptacle or shell 26 (Fig. 8) and the socket cavity 24 in which it is positioned provides an air-circulation passage in the regions intervening between the focusing or centering bosses 25 in all relative positions of the motor fan; and the swept-back attitude of the transverse socket-supporting member or web 23 affords a minimized interference to flow of cooling air generally upward through the top opening of the well in the base shell 15.

The advantages and economies afforded by the improved base structure will now be more readily appreciated with particular respect to the utility of a one-piece base shell and socket mount and the increased efficiency of the air flow afforded thereby, not only into the lamp housing generally but closely around the socket-receptacle shell 26 itself, together with the simple, economical, and effective mounting of the blower unit on the trunnion means so as to maintain the fan in the effective zones in all positions of tilting.

The formation of the base shell 15 with a deck or ledge 21 to overlie the free end of the tilt lever affords easy operating access to the tilt knob 50, and a long easy arc of movement for the lever system, giving smooth action throughout its range. Of importance also are the economies and efficiencies attending the attachment of the shell to trunnion lugs 37 and clamping the motor-bearer and trunnion cross-strap between the shell and lugs.

10 I claim:

1. In a projector, a base structure comprising a one-piece molded base shell having an upwardly opening well surrounded by depending sidewalls and a forwardly projecting deck having an elongated slot therethrough; an integral web spanning said well and having an integrally formed socket cavity therein; socket means in said cavity aligned by integral positioning bosses in said cavity; a base pedestal; opposite pivot lugs on said pedestal; a cross bar interposed between said lugs and said shell; fastening means engaged in said lugs and bar and said shell to secure said parts in assembly with the shell pivotable relative to the pedestal; blower means mounted on said bar in said well; a tilting lever pivoted on said bar and projecting horizontally through a sloping cam slot formation on said pedestal; and tilt operating means on said deck and connecting with said lever through said elongated slot for manipulation of the tilting lever.

2. In a projector, a base construction comprising a heavy pedestal member, a pair of pivot lugs on opposite sides of said pedestal member, a tilt lever pivotally connected with said pedestal member and extending horizontally through a cam slot member fixed on the pedestal member; and a base shell having an open bottom adapted to fit over said pedestal member, together with an open top overlying part, at least, of said pedestal member, said shell further including a substantially horizontal surface portion adjoining said open top and overlying said cam slot member and having a long arcuate slot concentric with the pivot point of said tilt lever, an extension of said lever projecting through said slot for manual engagement to pivot said lever and rock said shell relative to said pedestal member, said open top portion being adapted to be closed by a housing member seated thereon.

3. The construction set forth in claim 2 and further characterized by the provision of a lamp-supporting member formed integrally with said base shell and extending across said open top.

4. A construction according to claim 3 and further characterized by the provision of blower means for a lamp in said supporting member, and comprising a cross-strap held between said pivot lugs and base shell and having a motor fan secured thereon in a position substantially underlying said open top of the shell and the bottom of said lamp-supporting member; and a fan driven by said motor with its rotational axis substantially underlying said lamp-supporting member and lying along a line parallel to the pivotal axis of the shell relative to the pedestal member, so that said fan axis undergoes a minimized displacement between the limits of rocking movement of the shell and pedestal member.

5. In a projector, a base structure including a pedestal cast supporting a rockably and pivotally mounted one-piece molded shell having a top-opening well traversed by an integral web with an integrally formed lamp socket cavity therein, said cavity including a pair of opposite lamp focusing bosses lying along a fore-and-aft line parallel with the optical axis of the projector; a socket receptacle seated in said cavity in a fixed position against fore-and-aft motion between said bosses but having freedom of movement crosswise of said optical axis; and means adjustably mounting said socket receptacle on said web and adjustable to move the receptacle crosswise, as aforesaid.

75 6. In a projector, a projection lamp socket structure in

the molded base shell and comprising a supporting member having an annular cavity therein, a pair of centering bosses on diametrically opposite inside wall portions of said cavity; a socket shell of lesser diameter than said annular cavity seated in the latter between said bosses to fit closely into engagement with the latter to be held in a predetermined position thereby, but having freedom of movement crosswise of the diameter between said bosses; and adjustable screw means engaged with the socket shell and said supporting member and operable selectively to effect opposite crosswise adjusting movements of said socket shell.

7. In a projector, a pedestal member; a pair of pivot lugs pivotally attached to opposite sides of said pedestal member; a cross bar extending crosswise of said pedestal member and seated upon said lugs; a tilt lever having one end pivotally attached to a mid-portion of said cross bar to extend toward one end of the pedestal member; a stationary cam member at said one end of the pedestal member having formed therein an upwardly rising cam slot through which a free end portion of the tilt lever projects; and a motor fan unit fixed to said cross bar with a fan shaft substantially concentric with the pivotal axis of said lever, and a projector base member secured to said pivot lugs so that there is relative rocking movement between the base member and pedestal member responsive to pivotal movement of said tilt lever with the axis of said fan shaft undergoing a minimized displacement relative to overlying parts of said projector base member between the limits of rocking movement of the same relative to the pedestal member.

8. In a picture projector, a combination base-shell and socket-mounting structure comprising: a hollow one-piece body having a bottom opening and a top opening thereabove with integrally-formed cross web member having formed as an integral part thereof a seating formation for a lamp support with substantial open areas of airflow space about said seating formation for passage of cooling air upwardly there past from the region of said open bottom.

9. The construction of claim 8 further characterized by the provision of a pedestal body having a ring-like member having extensive open areas within its confines and dimensioned to lie within the bottom confines of said base shell; a cross-support and pivot means mounting the same crosswise of said ring-like member; air-moving means mounted on said cross-support to rock therewith and in position to displace lamp-cooling air upwardly through said open top and past said lamp-supporting formation; together with means interconnecting said base shell with said cross-support to rock therewith; and mechanism operable to rock said cross-support relative to said ring-like member.

10. A tilting base structure for a picture projector comprising a pedestal adapted to rest upon a support; a rockable member extending crosswise of said pedestal; means pivotally attaching said rockable member on the pedestal; a tilting lever having one end pivotally mounted on said

rockable member with an opposite end portion extending in a generally horizontal sense toward an end of the pedestal, an upright member on said pedestal extending crosswise of the latter near said end of the same and having an upwardly inclined cam slot therein extending in a direction generally crosswise of the pedestal; said opposite end of the tilt lever passing through said slot and acting in the latter responsive to pivotal movement of the lever to rock said rockable member relative to the pedestal, the rockable member being adapted to have connection with a member to be rocked therewith.

11. A lamp socket structure for a picture projector comprising a member having a cavity therein adapted to receive a socket mounting member having a crosswise dimension smaller than a crosswise dimension of said cavity and disposed in the cavity to rock in the latter at least in the direction of said dimensions, formations in the cavity closely flanking the socket mounting member to prevent rocking thereof as aforesaid, and means extending from said socket mounting member in opposite directions in the cavity along a line transverse to the line of the aforesaid crosswise dimension and adjustably attached to the cavity member by screw and spring means operable to rock the socket supporting member along the line of said transverse dimension.

12. A focusing type lamp socket for a picture projector comprising a body having a cavity, a socket shell in said cavity and smaller in diameter than the cavity at least in one predetermined transverse line of direction across the latter; stop means in the cavity flanking the socket shell along a diametric axis at substantially right angles to said transverse line and limiting rocking movement of the shell in the direction of said axis; transversely extending mounting members projecting from opposite sides of the shell; spring means acting on said mounting members to urge the shell in a predetermined direction from said transverse line, and attaching means loosely attaching said projecting members of the shell to said body so that the shell may move under urging of said spring means as aforesaid, the attaching means for at least one of said projecting members being adjustably movable back and forth along the line of action of the appertaining spring means for adjusting operation to rock the shell transversely into desired positions of adjustment for purposes of focusing a lamp in the socket.
